United States Patent Office

Des. 215,757
Patented Oct. 28, 1969

215,757

T-SQUARE

Humphrey Chang, New York, N.Y., assignor to Studio T Ltd., New York, N.Y., a corporation of New York

Filed Oct. 25, 1968, Ser. No. 14,180

Term of patent 14 years

Int. Cl. D10—08

U.S. Cl. D52—6

FIG. 1 is a perspective view of my novel design for a T-square;

FIG. 2 is an enlarged plan view;

FIG. 3 is an end view from the left side of FIG. 2; and

FIG. 4 is an end view from the right side of FIG. 2.

I claim:

The ornamental design for a T-square, substantially as shown.
